UNITED STATES PATENT OFFICE.

ALFRED DORMAN, OF PITTSFIELD, MASSACHUSETTS, ASSIGNOR TO E. D. JONES & SONS COMPANY, OF PITTSFIELD, MASSACHUSETTS, A CORPORATION OF MASSACHUSETTS.

BANDLESS ROLL FOR BEATING-ENGINES AND LIKE PAPER-MAKING MACHINES.

1,362,606.

Specification of Letters Patent. Patented Dec. 21, 1920.

Application filed January 9, 1918. Serial No. 211,077.

To all whom it may concern:

Be it known that I, ALFRED DORMAN, a citizen of the United States, residing at Pittsfield, county of Berkshire, and State 5 of Massachusetts, have invented certain new and useful Implements in Bandless Rolls for Beating-Engines and like Paper-Making Machines, fully described and represented in the following specification and 10 the accompanying drawings, forming a part of the same.

This invention relates to certain improvements in seating or securing grinding bars in position in washing, beating or refining 15 engines and similar machines used in the manufacture of paper stock, and the invention relates particularly to the positioning of grinding bars in the rolls of engines commonly known as Jordans, and of that class 20 of Jordan rolls known in the art as bandless rolls, that is, rolls in which no bands are shrunk on or otherwise positioned about the roll for holding the bars in position, this class of rolls having certain advantages 25 over types in which the bars are held in position by bands shrunk or otherwise secured about the roll.

It is the especial object of the present invention to produce a roll and bar of simple 30 construction, in which the bar may be firmly held in correct grinding position in the roll without the use of bands, and in which each bar may be readily and quickly put in position in the roll and removed therefrom without 35 disturbing or taking down the remainder of the roll.

It is a further object of the invention to produce a bar and roll in which the bar is assisted in maintaining its position in the roll 40 by the pressure of the work so that a very rigid and economical construction may be produced.

With these and other objects not specifically referred to in view, the invention 45 consists in certain novel parts and features of construction which will now be fully described in connection with the accompanying drawing, in which—

Figure 1 is a side view, partly in section, 50 showing the invention as embodied in a roll or plug of a Jordan refining engine;

Fig. 2 is a side view, partly broken away, of one of the grinding bars;

Fig. 3 is a top view, partly in section, of one of the grinding bars;

Fig. 4 is a sectional detail on an enlarged scale showing the manner of seating the bar in the roll;

Figs. 5, 6 and 7 are detail end views showing various methods which may be employed 60 for grouping the bars in the roll.

While the invention is capable of and intended to be used in various paper stock making machines employing grinding or cutting bars or knives, it has been shown and 65 will be described as embodied in the plug or core of a Jordan engine, and such a plug or core is shown in the drawings. Referring to these drawings, the plug or core, which is marked 1, may be of any suitable construction, but in the particular construction illustrated, is, as usual, a tapered hollow metal cylinder having an outer surface or rim 2. This cylinder has formed in its surface or 70 rim a plurality of longitudinal grooves 3, between which are left projecting ridges 4, these grooves affording retaining seats for the grinding bars 5.

In constructions embodying the invention, the grinding bars are rigidly held in position in the retaining grooves by coöperating fixed locking devices on the bars and support, thus dispensing with the use of bands, and in the best constructions these bars and the surface or rim of the plug will be so 85 formed that the bars may readily be assembled in the core or plug and held rigidly therein, the bars being partly held in position by the pressure of the work. While various constructions may be employed for 90 rigidly seating the bars in the grooves and for permitting a bar to be removed therefrom without disturbing the other bars, in the particular construction illustrated the plug is provided with peripheral grooves 95 or slots 6 which intersect at right angles the bar holding or retaining grooves 3 before referred to, and which may be termed positioning grooves or slots. These peripheral positioning grooves extend around the surface or rim of the core or plug, and are of sufficient dimensions to receive a locking pro-

jection formed on the bar and hereinafter referred to. These grooves 6 are widened at one side of their bottoms to form recesses 7, which extend longitudinally of the plug, 5 these recesses extending, as shown, toward the large or delivery end of the plug. By thus forming the grooves, above the recesses 7 there are provided holding or locking shoulders 8, these shoulders being produced 10 in the ridges or projections 4 before referred to.

The grinding bars or knives 5 will be provided with suitable locking devices which when the bar is in position will enter the 15 recesses 7 in the grooves 6 and go under the shoulders 8 so that the bar will be firmly held in position in the roll. While these locking means may be of various characters, for simplicity and cheapness these will be 20 formed by punching the bar to knock out projections or ears 9, which, as shown, project sidewise from the vertical plane of the bar. In assembling the bars in the roll, the bars are positioned as shown in dotted lines 25 in Fig. 4 and dropped into the longitudinal grooves 3, the projections or ears 9 on the bars entering the peripheral grooves 6. The bars are then driven with a suitable tool toward the right of Fig. 1, which causes the 30 projections or ears 9 to enter the recesses 7 and pass under the shoulders 8, and the bars are thus held rigidly in position. As the recesses 7 face in the direction of the course of the work through the machine, 35 the bars are assisted in maintaining their position by the pressure of the work and a very rigid structure is produced.

To remove a worn or broken bar from the core or plug, it is merely necessary to drive 40 the bar by means of a suitable tool backward until the projection 9 clears the shoulder 8, when the bar may be pried out. In the best constructions, to allow this to be easily effected, the bars are provided with 45 holes or slots 10 cut or punched therein, these holes or slots being located in the bar, so that when the bar is in the core or plug, the slots will come at about the rim or surface of the roll, so that a suitable tool may 50 be inserted in the slots and have a purchase against the roll surface for prying out the bar.

The bars may be arranged in the rolls in various ways, and in various groupings 55 and various lengths of bars may be employed. As illustrated, for instance, in Fig. 1, there may be a group of bars 11 which extend the length of the roll, these bars being associated with a group of bars 12 60 extending but half the length of the roll, or, if desired, a third group of bars 13, shorter than the bars 12, may be employed with the groups 11 and 12. Two bars may, if desired, be associated in the same longitudinal 65 groove, as shown in Fig. 5, and where such

arrangement is adopted, spacers 15 will be provided between the bars.

If desired, filling blocks or fillers 14, between the bars, may be employed as usual, to effect the proper circulation of the stock 70 through the machine. It will, of course, be understood that, as usual with Jordans, the plug or core shown will coöperate with the usual conical shell (not illustrated).

Each bar will have a sufficient number of 75 ears or projections 9 to effect a firm and rigid seating of the bars, and preferably and as shown, each bar will have at least two such projections, and there will be corresponding peripheral grooves 6 in the core. In the 80 construction shown, where the bars are of different lengths, a sufficient number of peripheral grooves will be provided to effect this.

It will be seen from the construction 85 shown and described that a very simple and efficient construction has been provided for seating grinding bars in their carriers or supports, and a construction in which each bar may be removed from the carrier or 90 support without the necessity of removing other bars, and in which the use of bands, which have to be shrunk or otherwise secured in position, are avoided. Furthermore, a very rigid construction is provided, 95 and one which is very durable. While the invention has been shown and described in its preferred form, it will be understood that certain variations from the precise form of supporting bars may be made, and such 100 bars may be used with different supports or carriers without departing from the invention.

What is claimed is:

1. In a machine of the class described, 105 the combination with a tapered grinding bar supporting cylinder, of longitudinally supporting grooves cut in the cylinder wall, peripheral grooves cut in the cylinder wall at right angles to the longitudinal grooves, 110 undercuts formed in the walls of the peripheral grooves extending toward the large end of the cylinder, the end walls of the undercuts forming abutments, and grinding bars having spaced locking projections punched out sidewise of the bar, said locking projections taking into the undercuts and abutting against the end walls of the undercuts toward the large end of the cylinder the bar being moved to locking or 120 unlocking position longitudinally of the cylinder and held against the abutments from endwise displacement by the pressure of the work through the machine.

2. In a machine of the class described, the 125 combination of a grinding bar support having longitudinal bar length supporting grooves, and locking shoulders adjacent the grooves, of grinding bars having locking projections seating under the shoulders, and 130

lifting notches located in the bar so as to be close to the surface of the support when the bar is in position.

3. A grinding bar or knife for beating and the like paper making machines, having spaced locking projections extending sidewise from the vertical plane of the bar, and lifting slots above the projections.

4. In a machine of the class described, in combination of the grinding bar support, of bar holding grooves, grinding bars, coöperating means between the bars and support

for locking the bars in position thereon, and means on the bars by which they may be lifted from the grooves.

5. A grinding bar or knife for beating and the like paper making machines having locking projections for locking the bar in a roll, and means above the projections by which the bar may be lifted from the roll.

In testimony whereof, I have hereunto set my hand.

ALFRED DORMAN.
